UNITED STATES PATENT OFFICE

WILLIAM H. CURTIS, OF DAYTON, OHIO, ASSIGNOR TO NATIONAL PUMPS CORPORATION,
OF DAYTON, OHIO, A CORPORATION OF OHIO

DESIGN FOR A PUMP CABINET

Application filed January 3, 1933. Serial No. 46,687. Term of patent 7 years.

To all whom it may concern:

Be it known that I, WILLIAM H. CURTIS, a citizen of the United States, residing at Dayton, in the county of Montgomery and State of Ohio, having invented a new, original, and ornamental Design for a Pump Cabinet, of which the following is a specification, reference being had to the accompanying drawing, forming part thereof.

In the drawing Fig. 1 is a front elevation of a pump cabinet, showing my new design; and Fig. 2 is a transverse sectional view of the same taken on the line 2—2 of Fig. 1.

I claim:

The ornamental design for a pump cabinet as shown.

WILLIAM H. CURTIS.
